UNITED STATES PATENT OFFICE

PAUL F. W. C. KRIPPENDORF, OF LYNN, MASSACHUSETTS

TELEPHONE INSTRUMENT

Application filed July 1, 1932. Serial No. 620,457.

This invention relates to movable telephone instruments of both the receiving and transmitting types.

Instruments of the sort mentioned are generally connected to a wall or floor outlet by flexible connector cords. As the instruments are handled in use, it is found that these cords become badly twisted, due to manipulation in the hand of the user, which shortens them so that the use of the instruments becomes inconvenient, and sometimes results in damage to the cords themselves.

An object of the present invention is to avoid this difficulty, and I have therefore provided a novel construction of such instruments having a member or guard, preferably in the form of a loop extending around the fingers which prevents turning of the instrument in the hand when in use, and necessitates its replacement in the same position from which it was taken, thus avoiding twisting the cord.

In accordance with a feature of the invention, the member or guard is made as a separate piece and is attachable to an instrument of the heretofore existing patterns.

These and other features of the invention comprising certain combinations and arrangements of parts will be apparent from the following description of a preferred embodiment of the invention shown in the drawing, in which

Fig. 1 shows an ordinary desk telephone transmitter and receiver as modified to embody the invention;

Fig. 2 shows a combined receiver and transmitter; and

Fig. 3 shows attachable guards applied to the ordinary desk instrument.

In Fig. 1 the transmitter 10 and receiver 12 are generally of the familiar type but are provided respectively with loops 14, 16 which, in the illustrated instruments, are molded, cast or otherwise integrally formed with the instruments carrying them. They are so shaped that the spaces 18, 20 included between them and their respective instruments are ample to receive comfortably the four fingers of the hand used in holding them. These loops or guard members thus prevent

rolling the instruments in the hand while they are being held, and insure that they will be replaced in the positions from which they were taken, thus avoiding twisting the cords 22 and 24.

Fig. 2 shows a combined receiver and transmitter 26 having a similar guard loop 28, the operation of which will be clear without further description.

Fig. 3 shows the ordinary desk receiver and transmitter equipped with attachable guards 30, 32 respectively. These may be made of any desired substance, as molded fiber, shaped to embrace the part to which they are attached, and fastened in place by small screws or bolts 34, as shown.

Having described my invention, what I claim as new and desire to secure by Letters Patent of the United States is:

1. A telephone instrument having a guard member arranged to receive the fingers of the hand between it and the main body of the instrument, to prevent rolling the instrument in the hand. 70

2. A telephone instrument having a guard member attached thereto at its ends and forming an aperture shaped to receive the fingers of the hand, to prevent rolling the instrument in the hand. 75

3. An attachable guard for a telephone instrument shaped to form an aperture to accommodate the fingers of the hand, to prevent rolling the instrument in the hand. 80

4. A guard for a telephone instrument having means for attaching it to the instrument, and shaped, when so attached, to bound a space to accommodate the fingers of the user, to prevent rolling the instrument in the hand. 85

5. A telephone receiver equipped with a guard member extending from a point adjacent one end of the instrument to a point adjacent the other end, and shaped to accommodate, between it and the receiver, the fingers of the user to prevent rolling the receiver in the hand. 90

In testimony whereof I have signed my name to this specification.

PAUL F. W. C. KRIPPENDORF.
